UNITED STATES PATENT OFFICE.

ROBERT E. WILLIAMS AND WILLIAM A. TRAMMELL, OF DALLAS, TEXAS;
SAID TRAMMELL ASSIGNOR TO SAID WILLIAMS.

COMBINED FLOUR AND MEAL BIN AND FLOUR-SIFTER.

SPECIFICATION forming part of Letters Patent No. 328,444, dated October 13, 1885.

Application filed September 19, 1884. Serial No. 143,469. (No model.)

To all whom it may concern:

Be it known that we, ROBERT E. WILLIAMS and WILLIAM A. TRAMMELL, of Dallas, in the county of Dallas and State of Texas, have 5 invented certain new and useful Improvements in Combined Flour and Meal Bins and Flour-Sifters; and we do hereby declare that the following is a full, clear, and exact description of the invention, which will enable 10 others skilled in the art to which it appertains to make and use the same, reference being had to the accompanying drawings, which form a part of this specification, and in which—

Figure 1 is a front view of our improved 15 flour sifter and bin. Fig. 2 is a vertical sectional view of the same. Fig. 3 is a side view with a portion broken away, and Fig. 4 is a vertical section on line $x x$, Fig. 2.

Similar letters of reference indicate corresponding parts in all the figures.

Our invention has relation to that class of flour-sifters in which the sifting mechanism is secured at the lower end of a bin or receptacle containing the flour or meal; and it consists 25 in the improved construction and combination of parts of such a device in which the bin is divided in two receptacles opening into the sifting mechanism, and having suitable cut-off slides, as hereinafter more fully 30 described and claimed.

In the accompanying drawings, the letter A indicates the bin, which is divided longitudinally by a partition, B, and which is formed at its upper end with a laterally-projecting flange, C, and at its lower end with a contracted neck, D, having a laterally-projecting flange, E, a distance from its end. This contracted neck has a laterally-projecting pin or lug, F, immediately under the flange, 40 and a perforated spring-catch, G, secured to the upper edge of the sifter H, which is of the usual construction, and for which we make no claim, engages the said lug, securing the sifter to the neck, the said sifter fitting upon 45 the neck. The sides of the bin contract toward the flange around the neck, the said flange being at the base of the neck, and two slides, I I, or cut-off valves slide in ways J in the neck, passing through slots K in the sides

of the neck and resting upon the flange of the 50 neck.

A sliding cover, L, having downwardly and inwardly bent flanges M, slides upon the laterally-projecting flanges at the upper edges of the bin, covering the open top of the same, 55 and may be slid to one side or the other for the purpose of allowing either one of the receptacles to be opened for filling it, or for any other purpose, while the other receptacle remains closed. 60

Two loops, N N, are secured upon the sides of the bin at the lower ends of the straight sides of the bin, and serve for the insertion of two legs, O O, by means of which the device may be supported standing, a third leg, P, 65 being permanently secured to the rear side of the bin, while the two other legs are removably inserted in their loops or sockets. The permanent leg extends above the upper end of the bin, and has a perforation, Q, by 70 means of which it may be suspended by nails upon the wall when it is not desired to have the bin stand, the removable legs being taken out of their loops or sockets.

A stirrer or agitator, R, is journaled in the 75 receptacle intended for flour, and consists of a shaft, S, having a number of transverse pins or rods, T, and having a crank, U, for turning it, and serves for the purpose of stirring the flour, if it should become clogged. 80

Having thus described our invention, we claim and desire to secure by Letters Patent—

1. A combined flour and meal bin and flour-sifter consisting of a bin having the sifter at its lower end and formed with loops or sockets at the lower ends of its straight sides, two legs fitting with their upper ends in the said loops or sockets, and a leg permanently secured to the rear side of the bin, extending above the upper end of the bin, and having 85 a perforation at its upper end and in its lower portion, as and for the purpose shown and set forth.

2. A bin having a vertical partition and having its sides contracting at its lower end, 95 forming a neck, and having a laterally-projecting flange at the upper edge of its forward and rear side and a laterally-projecting flange

around the base of the neck, the sliding cover having the downwardly and inwardly bent side edges fitting over the top flanges of the bin, and the cut-off slides sliding in ways at the lower end of the bin above the laterally-projecting flange, as and for the purpose shown and set forth.

In testimony that we claim the foregoing as

our own we have hereunto affixed our signatures in presence of two witnesses.

ROBERT E. WILLIAMS.
WILLIAM A. TRAMMELL.
